UNITED STATES PATENT OFFICE.

JESSE L. FRIESNER, OF LIMA, OHIO.

BOTTLE HOLDER.

Application filed August 16, 1926. Serial No. 129,551.

This invention relates to a holder designed primarily for milk bottles, one of the objects of the invention being to provide a structure in which empty bottles can be placed and 5 from which they can be removed readily, means being included in the structure which allow the milkman, after placing filled bottles in the holder, to quickly lock them in place so that they cannot be removed except 10 by a person having a proper key.

Another object is to provide a device of this character which is simple, compact and durable.

With the foregoing and other objects in 15 view which will appear as the description proceeds, the invention resides in the combination and arrangement of parts and in the details of construction hereinafter described and claimed, it being understood that 20 changes in the precise embodiment of the invention herein disclosed may be made within the scope of what is claimed, without departing from the spirit of the invention.

In the accompanying drawings the preferred form of the invention has been shown.

In said drawings,

Figure 1 is a plan view of the device.

Figure 2 is a front elevation.

Figure 3 is a section on line 3—3, Figure 30 2.

Figure 4 is a bottom plan view.

Figure 5 is a section on line 5—5, Figure 35 3.

Figure 6 is a view similar to Figure 5 showing the doors unlocked.

Figure 7 is a side elevation.

Figure 8 is a perspective view of the keeper, a padlock therein being indicated by broken lines.

40 Referring to the figures by characters of reference 1, designates a base plate having front and side flanges 2, 3 and 4 supporting a cover plate 5, the two plates being held together in any suitable manner, as by means 45 of rivets 6 extending through the corner portions thereof. An upstanding attaching plate 7 is preferably formed integral with the bottom plate 1 and constitutes the back of the structure. Formed within the bottom 50 plate adjacent the center thereof are front and back alining slots 8 and 9 respectively and that portion of the cover plate 5 over the slot 9 and the rear portion of the slot 8 is elevated as at 10 to provide an enlarged 55 space 11 between the two plates.

Slots 12 are formed in the front flange 2

of the bottom plate and rounded recesses 13 are formed in the plate 1 back of these slots. Similar recesses 14 are formed in the cover plate 5 directly over the recesses 13.

Pivotedly mounted between the plates 1 and 5 are arcuate jaws 15 and 16 arranged in pairs, the jaws 15 being located between the recesses 13 while the jaws 16 are located between the side flanges of the bottom plate 65 and the recesses 13. The jaws of each pair are oppositely disposed and the pivots 17 of the jaws are located between the ends thereof so that each jaw is thus formed with a short rear arm and a long front arm as 70 shown particularly in Figure 3. When the forward ends of the jaws 15 and 16 are spread apart, the inner ends of said jaws will be extended toward each other and be exposed between the recesses 13 and 14 as 75 indicated by broken lines in Figure 3. When the forward ends of the jaws are closed toward each other, however, said jaws will substantially register with the walls of the two recesses as shown by full lines. A bolt 18 80 in the form of a flat plate is slidably mounted between the plates 1 and 5 and is guided by a stud 19 slidable in the slot 8 and by clamping screw 20 slidable within a slot 21 in the cover plate 5. When this plate 18 85 is in its rearmost position, the jaws can be opened as shown by broken lines in Figure 3. When the bolt 18 is moved forwardly against the flange 2, however, it will fit snugly between flat edges 22 of the jaws 16 and hold 90 said jaws against pivotal movement.

Tiltably mounted within the space 11 is a tumbler 23 in the form of a plate normally resting on the bottom plate 1. This tumbler has a V-shaped stem 24 projecting backwardly therefrom and slidably and tiltably mounted between guide plates 25 or engaged by any other suitable means. Obviously as long as the tumbler is in its normal position on the plate 1 it is impossible for the bolt 18 95 to be slid rearwardly out of engagement with the jaws 15. However by lifting the tumbler so that the front edge thereof will be out of the path of the bolt 18, said bolt can be slid backwardly to position under the tumbler as 100 shown for example in Figure 6.

For the purpose of actuating the tumbler so as to release the bolt there is provided a rod 25 extending transversely under the plate 1 and journaled within brackets 26 105 provided therefor. At one end of this rod is a radial arm 27 supported directly under

and adapted to work within the slots 9. The other end of the rod has a crank arm 28 supported beyond the side of the structure and adapted normally to rest within a U-shaped keeper 29 secured to the plate 5 and extending through the side flange 4. When this crank arm is seated within the keeper it can be secured against movement by means of a padlock 30 insertable through apertures 10 31 in the keeper.

In using the structure the same is positioned over a step or other support so that after the neck portion of a milk bottle has been secured in the recesses 13 and 14, it 15 becomes impossible to withdraw the bottle by lowering it. However, if the bottle is provided with a rib around the mouth thereof, it is not necessary to provide a support beneath the holder. Instead the bottle, when 20 locked in the structure, can be supported by the wall of the recess 14 engaging the annular bead on the mouth of the bottle.

The user rotates the rod 25 so as to cause 25 arm 27 to swing upwardly within slots 9 and tilt the keeper 23. Thus the forward edge of the keeper will be raised above the level of the bolt 8 and said bolt can be slid backwardly under the keeper as shown in Figure 6. With the bolt thus located the jaws 15 and 16 can be swung apart, a bottle can be placed between them and, when thus inserted, will come against the rear arms of the jaws and cause the forward arms to swing toward each other to the full line position 35 shown in Figure 3 as well as in Figure 1. Thus an empty bottle will be supported and the crank arm 28 can then be returned by the user to the keeper 29 where it can be strapped by means of the padlock 30 or 40 other suitable device provided for that purpose. When the milkman removes the bottle he merely pulls it forwardly. This will cause the jaws to swing open. The filler bottle is then inserted into the recesses 13 and 45 14 whereupon the jaws will again pull together as before explained. The milkman then loosens the screw 20 and, by means of said screw, pulls the bolt 18 forwardly to position between the straight edges 22 of the jaws 15. When the bolt reaches this 50 position the keeper 23 will drop behind the bolt. Consequently the jaws are held against movement and it becomes impossible to remove the bottle. The bottle can only be 55 taken away after the person holding the proper key removes the padlock 30 and swings the arm 28 upwardly. This will cause the keeper 23 to tilt upwardly whereupon the user can slide the bolt 18 backward-

ly to the position shown in Figure 6. This 60 releases the jaws 15 and permits removal of the bottle or bottles.

It will be apparent that this device can be equipped with one or more bottle receiving recesses but in any event the one rod 25 65 will act to unlock the jaws of all of the recesses simultaneously.

For preventing tampering with the tumbler 23 there is provided a recessed guard plate 32 secured to the bottom plate 1 and 70 extending under the slots 8 and 9. The rod 25 is journaled in one side wall of this recessed guard plate.

What is claimed is:

1. The combination with a structure having a bottle receiving recess and opposed jaws pivotally mounted at opposite sides of the recess, each jaw having an outer arm and an inner arm, the corresponding arms of the jaws converging, of a bolt slidable into engagement with one of the jaws, a tumbler adapted to rest upon the bolt, said tumbler being movable by gravity into position back of the bolt when the bolt is brought to jaw engaging position, and means for shifting the tumbler to release the bolt. 75

2. The combination with a structure having a bottle receiving recess and opposed arcuate jaws pivotally connected to the structure at opposite sides of the recess, each 90 jaw having an inner arm and an outer arm, of a bolt slidable into engagement with one of the jaws to hold it against pivotal movement, a tumbler adapted to be supported by the bolt, said tumbler being movable by gravity into position back of the bolt to hold the bolt against movement away from the jaw engaged thereby, a tumbler lifting arm, and means for locking said arm against movement. 95

3. The combination with superposed connected plates having registering bottle receiving recesses, and opposed arcuate jaws pivotally mounted between their ends and extending between the plates, said jaws being disposed at opposite sides respectively of the recesses, of a bolt slidable between the plates, a tumbler normally resting thereon, said bolt being shiftable into engagement with one of the jaws to hold the jaw against 105 pivotal movement and to release the tumbler for movement into the path of the bolts, means for shifting the tumbler to release the bolt, and means for fastening said shifting means against movement. 110

In testimony that I claim the foregoing as my own, I have hereto affixed my signature.

JESSE L. FRIESNER. 115
